2,009,360

PEN STAND

Henry Ludwig Koch, Milwaukee, Wis., assignor
of one-half to Theodore Kramer, Milwaukee,
Wis.

Application October 16, 1933, Serial No. 693,727

4 Claims. (Cl. 120—108)

This invention relates to pen stands and more particularly to a pen stand adapted for use with a fountain or other pen for placement on a desk.

An object of the invention is to provide a device of the type which may readily be moved from place to place as may be found necessary due to the amount of space available where work with a pen is being done.

Another object of the invention is to provide a device of the type which, when placed, will securely fasten itself and will not readily be dislodged with ordinary care.

Another object is to provide a device for the purpose which will be very economical of manufacture and highly efficient in use.

The constructional features of the improved pen stand will now be described, and the novelty residing in the same will be pointed out in the appended claims.

20 In the accompanying drawing:

Fig. 1 is a sectional view of a pen stand embodying my invention showing a fountain pen held therein and indicated by a dotted line.

Fig. 2 is a perspective view in elevation of the device.

Referring more particularly to the drawing, the numeral 10 refers generally to the pen stand. The basal portion 11 is formed with a convex surface at 12 for use of the vacuum principle in attachment of the device to a plane surface. In the preferred form of the invention the upper portion or sleeve 13 is obliquely disposed. The upper inner end of the sleeve has the inwardly directed, rib or flange 14 which serves to more adequately secure a pen which may be placed therein. The inner end of sleeve 13 is formed with a concave surface at 15 which also serves to invoke the vacuum function in retaining there-in a pen cap.

40 In use, the socket 13 is maintained to hold the

cap 16 of a fountain pen 17, after which the pen proper may be removed and re-inserted into the cap. It will readily be seen that the socket, due to the vacuum effect, will very firmly hold the cap against withdrawal and that the annular flange 14 will assist in this function, and that the concavity 12 of the basal portion 11 will employ the vacuum principle for the placement and securing of the entire unit in any desired location on a desk or other plane surface on which it may be used.

The device is capable of various modifications in structure without departing from the spirit of the invention or the scope of the appended claims.

The device is very easily manufactured by 15 pouring rubber in granulated form into a mould which is heated to fuse the rubber and thus form the finished product.

Having thus described my invention, what I claim and desire to secure by Letters Patent of 20 the United States, is:—

1. An article of the class described formed of one piece of resilient material comprising a basal vacuum suction cup, and an upwardly disposed sleeve.

2. An article of the class described formed of one piece of resilient material comprising a basal downwardly disposed vacuum suction cup, and an upwardly disposed sleeve.

3. An article of the class described formed of 30 one piece of resilient material comprising a basal vacuum suction cup, an upwardly disposed sleeve, and an inner flange adjacent the mouth of said sleeve.

4. An article of the class described formed of 35 one piece of resilient material comprising a basal downwardly directed vacuum suction cup, an upwardly disposed sleeve, and an annular inner flange within said sleeve.

HENRY LUDWIG KOCH. 40
